B. SCHMELZER.
ROTARY BLOWER.
FILED JUNE 22, 1920.

UNITED STATES PATENT OFFICE.

BRUNO SCHMELZER, OF JERSEY CITY, NEW JERSEY.

ROTARY BLOWER.

Application filed June 22, 1920. Serial No. 390,889.

To all whom it may concern:

Be it known that I, BRUNO SCHMELZER, a citizen of the Republic of Poland, and resident of Jersey City, in the county of 5 Hudson and State of New Jersey, have invented certain new and useful Improvements in Rotary Blowers, of which the following is a specification.

This invention relates to rotary blowers, 10 and has for its principal object the provision of an efficient and novel device of this character which embodies means for projecting a continuous and even current of air of maximum force; a further object being to 15 provide means for projecting the air in any one of several directions from a fixed housing or casing.

In carrying out my invention I employ 20 scoop-shaped vanes of the general character disclosed in my Letters Patent No. 1,197,766, Sept. 12, 1916, for propelling device, but of improved contour, a housing having lateral inlets for air, and a normally open peripheral outlet, and other novel features herein- 25 after fully described and specifically set forth in the annexed claims.

In the accompanying drawings forming 30 part of this specification, Figure 1 is a perspective view of one of the vanes forming part of my invention. Fig. 2 is a side view of the blower; Fig. 3 is an edge view thereof; and Fig. 4 is a cross section of the vane taken on the line 4—4 of Fig. 1.

The propelling means for driving the air 35 comprises a plurality of vanes 1, of approximately scoop-shaped contour respectively embodying a back 2, of segmental curved contour having its convexity forward and its concavity rearward of its annular direction of travel, (indicated by the arrow α), and having side wings 3 with edges that curve outwardly and forwardly and converge at their rearwardly extending outer or tip-end parts and extend from a straight- 40 line base part 5, which is fixed to and parallel with a shaft 7, said back 2 extending at its point of intersection with said shaft tangentially from the periphery thereof. The blades thus formed are of scoop-shape having sides projecting therefrom and brought 45

to a point at each end, the center of the trough of the scoop being forward in the direction of travel.

The said shaft 7 is journaled through bearings 8 which form part of spider-like 55 hangers 9, extended across the air-inlet openings 10 of a housing 11 which is supported by a suitable base 12.

One end of the shaft 7 is journaled 60 through a standard 13, and said end is provided with a pulley 14 adapted for engagement with a suitable belt and motor-means for driving the propeller, in the common and well known manner.

The housing 11 has a straight-line flat up- 65 right sides and a semi-circular periphery for snugly encasing the propeller and cooperating therewith.

As a means for ejecting air I provide a 70 cylindrical nozzle 16.

In the operation and use of the invention the propeller is given rapid rotary movement by means of its pulley 14 and any suitable motor-actuated means for rotating said pulley; this movement draws air through 75 the lateral openings of the sides of the housing and ejects it through the opening 15 of the nozzle 16, and owing to the peculiar shape of the propeller blades friction is minimized and a maximum of efficiency is 80 attained.

Having thus described my invention, what I claim as new and desire to secure by Letters Patent, is:—

1. In a device of the class described, a 85 rotary blower having vanes comprising a back with a relatively wide base, a rearwardly extending contracted tip and sides projecting therefrom so as to be of scoop-shape, the central part of the trough of the 90 scoop being forward in the direction of rotation and the contour of the faces of the sides thereof being approximately in the shape of a crescent.

2. In a device of the class described, a 95 rotary blower having vanes comprising a back with a relatively wide base, a rearwardly extended contracted tip and sides projecting therefrom and brought approximately to a point at each end thereof, so as 100

to be of scoop-shape, the central part of the trough of the scoop being forward in the direction of rotation.

3. In a device of the class described, a rotary blower having vanes comprising a back with a relatively wide base, a rearwardly extending tip and sides projecting therefrom, the said sides and back converging at the tip so as to be of scoop-shape, the

central part of the trough of the scoop being forward in the direction of rotation and the contour of the faces of the sides thereof being approximately in the shape of a crescent. ¹⁰

Signed at the city of New York, in the county of New York and State of N. Y., 15 this 27 day of May, A. D. 1920.

BRUNO SCHMELZER.
